UNITED STATES PATENT OFFICE.

LEO MORTON ZANDER, OF KANSAS CITY, MISSOURI.

TOY VEHICLE.

Application filed August 4, 1927. Serial No. 210,611.

My invention relates to improvements in toy vehicles.

One of the objects of my invention is to provide novel means for steering a vehicle.

5 A further object of my invention is to provide novel guard means by which the occupant of the vehicle may stand thereon without danger of falling sidewise therefrom.

10 A further object of my invention is to provide a novel vehicle of the kind described, which is simple, cheap to make, durable, not liable to get out of order, which is easily operable by a small child, and which will afford amusement to the operator.

15 The novel features of my invention are hereinafter fully described and claimed.

In the accompanying drawing, which illustrates the preferred embodiment of my invention,

20 Fig. 1 is a side elevation of my improved vehicle.

Fig. 2 is a top view of the same.

Fig. 3 is a rear elevation of the same.

25 Fig. 4 is an enlarged longitudinal sectional view through one of the hand holds and parts connected therewith.

Fig. 5 is a vertical sectional view through the steering post and parts connected therewith.

30 Similar reference characters designate similar parts in the different views.

The vehicle is provided with a base member which may comprise a horizontal board 1 to the forward end of which is attached

35 the rear end of a forwardly and upwardly extending central bar 2.

A tubular steering post has its lower end fastened to the bar 2, said post being designated by 3, and having fastened to it a bar

40 4 to which is fastened centrally the trans-

verse portion 5 of a U shaped guarding and guiding member, the arms 6 of which extend horizontally rearwardly and then downwardly, their lower ends being fastened to

45 the board 1 at the rear end thereof and at

opposite sides respectively of a notch 7 in

the rear end and center of the board 1.

The arms 6 serve as guard rails for keeping a person standing on the board 1 from falling sidewise therefrom. They further serve as guiding means for two hand holds 8, which are tubular and respectively reciprocative on the horizontal portions of the arms 6.

50 55 For supporting the rear end of the support comprising the board 1, bar 2, post 3

and U shaped member 5—6, there is fastened to the under side of the board 1 a horizontal arched axle 9 on the ends of which are mounted two rotatable carrying wheels 10.

For supporting the front end of the support, and also for steering the same, there is provided a carrying member which may comprise a steering wheel 11, which is rotatably mounted on and between two arms 12 of an oscillative member 13 which is oscillatively mounted in and which extends above the post 3. Said member 13, above the post 3 has a square portion 14 which is fitted in a square hole in a cross bar 15, the upper end of the member 13 being threaded and having fitted on it a nut 16 which bears against the cross bar 15, the latter resting on a shoulder 17 at the lower end of the square portion 14.

Two rods 18 have their rear ends pivoted respectively to two studs 19 provided respectively on two caps 20 with which the front ends of the hand holds 8 are respectively provided. The front ends of the rods 18 are respectively pivoted to the cross bar 15 at opposite sides of the member 13.

In operating the vehicle, the operator stands on the board 1 between the arms 6 and 85 grasps the hand holds 8 with his hands. The rear end of the board 1 is notched to enable the operator to easily thrust his foot to the ground for propelling the vehicle.

To steer the vehicle to the right, the operator pulls backwardly on the right hand hold 8 and pushes forwardly on the left hand hold. This will swing the cross bar 15 by means of the rods 18, thus turning the wheel 11 to the right by means of the member 13 95 and its arms 12.

To steer the vehicle to the left, the hand holds are moved in the opposite directions from that just described.

To run straight ahead, the hand holds are 100 moved to positions in the same transverse vertical plane, thereby holding the wheel 11 in the straight ahead position.

I do not limit my invention to the structure shown and described, as many modifications, within the scope of the appended claims, may be made without departing from the spirit of my invention.

What I claim is:—

1. In a toy vehicle, a support, for a person, having a steering post and having a U shaped guiding member fastened at its mid-

dle portion to said post and having its arms fastened to said support, means oscillative on and supporting said support, a steering member carrying and movable with said oscillative means, two hand holds reciprocative respectively on the arms of said U shaped guiding member, and means connecting said hand holds and said oscillative means by which the latter is oscillated when said hand holds are simultaneously moved in opposite directions.

2. In a toy vehicle, a support, for a person, having a tubular steering post and having a U shaped guiding member attached to said post and to said support, a member oscillative in and supporting said post, a cross bar fastened to said oscillative member, a steering member supporting and movable with said oscillative member, two hand holds respectively reciprocative on the arms of said U shaped guiding member, and two rods respectively connected at one set of ends to said hand holds and connected at their other

ends to said cross bar at opposite sides respectively of said oscillative member. 25

3. In a toy vehicle, a support, for a person, comprising a base member, a tubular steering post on said base member, and a U shaped guard member fastened at its transverse portion to said post and having its arms extending rearwardly and downwardly and fastened at their lower ends to said base, a member oscillative in and supporting said post, a cross bar fastened to said oscillative member, a steering supporting member mounted on said oscillative member and supporting said oscillative member, two hand holds respectively reciprocative on the arms of said U shaped member, and two rods respectively connected to said hand holds and connected to said cross bar at opposite sides respectively of said oscillative member. 30 35 40

In testimony whereof I have signed my name to this specification.

LEO MORTON ZANDER.
